HYDROMASSAGE UNIT FOR SWIMMING POOL

Roy A. Jacuzzi, Morago, and Peter L. Kosta, Lafayette,
Calif., assignors to Jacuzzi Research, Inc.

Filed May 10, 1971, Ser. No. 142,087

Term of patent 14 years

Int. Cl. D24—99

U.S. Cl. D83—1

FIG. 1

FIG. 2

FIG. 4

FIG. 3

FIG. 5

FIG. 6

FIG. 1 is a perspective view of a hydromassage unit showing our new design;

FIG. 2 is a front view in elevation of said device;

FIG. 3 is a view in elevation of one side of the device of FIG. 1, the opposite side being the same except for absence of the screen installation;

FIG. 4 is a top plan view of the hydromassage unit;

FIG. 5 is a rear view in elevation of the said device taken in the direction of line 5—5 of FIG. 3, and

FIG. 6 is a bottom plan view taken in the direction of line 6—6 of FIG. 3.

We claim:

The ornamental design for a hydromassage unit for swimming pool, as shown and described.
